UNITED STATES PATENT OFFICE.

WALTER G. WERBECK, OF CHICAGO, ILLINOIS.

WATER-GAGE PROTECTOR FOR STEAM-BOILERS.

1,223,456.

Specification of Letters Patent.

Patented Apr. 24, 1917.

Application filed March 17, 1916. Serial No. 84,920.

To all whom it may concern:

Be it known that I, WALTER G. WERBECK, a citizen of the United States, residing at Chicago, in the county of Cook and State 5 of Illinois, have invented certain new and useful Improvements in Water-Gage Protectors for Steam-Boilers, of which the following is a specification.

This invention relates to improvements in 10 water gage protectors for steam boilers and it is adapted primarily for use upon marine boilers and stationary steam boilers. The fact that the water gages of steam boilers comprise a glass tube in communication with 15 the boiler often leads to serious accidents, in the use of gages of ordinary construction, due to the bursting of the tube from internal pressure and the projecting of fragments of glass along with steam and boiling 20 water through the atmosphere. One of the objects of this invention is to avoid such accidents, and it consists of a sectional hinged glass-protector, open at each end, which encompasses the water tube and which 25 is provided in its swinging section with removable strips of a very hard glass through which the water level in the gage may be easily read; the relatively stationary section of the protector comprising a metallic 30 back that may consist of a metallic blank whereon differently colored stripes are painted to enable a clear reading of the water level in the gage from a distance.

Another object is to provide a protector 35 wherein the transparent glass strips can be readily cleaned and instantly removed when desired or necessary. A further object is to provide a protector so constructed as to permit almost instantaneous insertion or removal of the gage glass, the only tool needed for this operation being an ordinary monkey wrench. While it is true that the danger of 40 injury to those about a marine or stationary steam boiler due to the accidental breakage 45 of a water glass is reduced on account of the usual height of the water glass from the ground in these cases, it is also true that bursting of such glasses has, in many cases, been known to take place immediately upon 50 insertion of a new glass in position and this accident often results in the injury of the person or persons engaged in installing the glass. It is an object of this invention to obviate accidents of this nature.

55 With the foregoing and other objects in view the invention consists in the combina-

tion and arrangement of parts to be herein-after fully described in this specification, pointed out in the appended claims and illustrated in the accompanying drawings 60 which form a part of said specification and in which—

Figure 1 is a side view of my improved water gage protector showing its application to a steam boiler.

Fig. 2 is a front view of the same with the swinging section, or door, in open position.

Fig. 3 is a cross section taken on line 3—3 of Fig. 1, the door being shown closed in full lines and open in dotted lines.

Fig. 4 is a fragmentary front view of the back.

Like reference characters denote corresponding parts throughout the several views.

The reference numeral 1 denotes a steam boiler provided with the hand valves 2 and 3 which lead respectively to the steam and water spaces of the boiler. Extending toward each other and in alinement with each 75 other are the nipples 4, 5 which carry the gage nuts 6, 7 that carry the gage glass 8. My protector comprises a casing approximately cylindrical in shape and open at top and bottom and composed of a stationary 80 section and a movable or door-like section. The stationary section is a one-piece section and consists of a back 9 having two pairs of alined ears 10 and 11 through which the ends of the staples or U-shaped bails 12 pass, the 85 closed ends of said members encircling the valves 2, 3 to support the back 9 rigidly in position. The ends of the material composing the bails are threaded for engagement with the nuts 13 to afford means for rigidly 90 securing the ears of the back to the said 95 bails.

To the ears 10, 11 the swinging section or door-like member 14 is secured by removable pintles 15 and to open the door it is but 100 necessary to withdraw one pintle and permit the section 14 to swing upon the remaining one. The member 14 is formed with a plurality of apertures 16 each of which is closed by a removable strip of hard glass 17 105 which is normally disposed in the recessed portions 18 of this member. Through any of the glass strips 17 the height of the water in the gage glass may be readily observed.

Referring again to the back 9, the same 110 may be formed of a solid blank of material which may be painted or colored in stripes

as shown at 19 in Fig. 4 to form a reflector and facilitate the reading of the gage glass.

What is claimed is:—

1. The combination with oppositely disposed nipples, of gage nuts, a gage glass connecting said gage nuts and readily releasable therefrom, a sectional member comprising a stationary element and a movable element inclosing said gage glass, said stationary element having applied thereto a striped coating of light-reflecting material, said movable element being formed with longitudinal apertures and having removable glass strips normally closing said apertures, threaded bails adjustably supporting said stationary element and nuts for the threaded portions of said bails for locking them in adjusted position with relation to said stationary element.
2. The combination with oppositely disposed nipples, of gage nuts, a gage glass connecting said gage nuts and readily releasable

therefrom, a sectional member comprising a stationary element and a movable element in closing said gage glass, said stationary element having applied thereto a striped coating of light-reflecting material, said movable element being formed with longitudinal apertures and having removable glass strips normally closing said apertures, threaded bails adjustably supporting said stationary element and nuts for the threaded portions of said bails for locking them in adjusted position with relation to said stationary element. 25 30

In testimony that I claim the foregoing 35 as my own I have hereto affixed my signature in the presence of two subscribing witnesses.

WALTER G. WERBECK.
